CONTAINER

William Froehlich, Baltimore, Md.

Application April 8, 1935, Serial No. 15,203

4 Claims. (Cl. 206—56)

My invention relates to a container, and is very useful in pocket size tobacco or other such containers that are emptied part at a time, and in which the contents at the bottom may be reached

5 as readily as the contents nearer the top.

Among the objects of my invention are to make a container that has a slideable bottom that may either be pushed progressively up as the contents are used up, or may be pushed up half the length 10 of the box when the contents are substantially one-half used.

Another object of my invention is to place strips at the sides of the sliding bottom that will permanently hold the bottom in its new position.

15 Another object of my invention is to use strips that will be out of the way of the lining and contents of the box, and that will quite rigidly support the bottom, and also limit its maximum upward movement.

20 Another object of my invention is to put an outside cover over the lower end of the container to make a compartment for matches.

Other objects and advantages of my invention will be apparent from the following description 25 and accompanying drawings, in which:

Figure 1 is a front elevation, showing in dotted lines the bottom pushed up and held up by my new holding means.

Figure 2 is similar side elevation.

30 Figure 3 is a bottom view of the can, showing in dotted lines the lower cover partially withdrawn.

Figure 4 is an enlarged partial sectional view of the invention through the center of the can 35 before the bottom has been pushed up.

Figure 5 is an enlarged side view, with the side of the can cut away.

Figure 6 is an enlarged sectional view of the can, looking down on the bottom after it has 40 been pushed up.

Figure 7 is an enlarged perspective view of my new holding means in holding position on the bottom of the can.

Figure 8 is an enlarged horizontal view before 45 the bottom is pushed up, with the top cover and contents removed from the can.

Figure 9 is a modified form of holding means.

In the drawings similar numerals refer to similar parts throughout the several views.

50 The can body 1 has a top cover 2 thereon, and a horizontally slideable bottom cover 3. The lower end walls of the can are curled outwardly, as at 4, and the bottom cover has parallel curled edges

55 sliding over the body curl 4 and an end curl 6 to limit the movement of said cover when it is

completely in place. Punch mark 7 releasably holds the cover in place, closed, and punch marks 8 releasably limit its withdrawal, in slidingly moving the cover to open position.

Bottom 9 has a vertical flange 10 extending around it. Very thin resilient strips 11 extend up into the can, at its sides, and they are held fast to the can body by being curled into curl 4, as clearly shown in Figure 4. The flange 10 of bottom has slots 12 in the ends thereof. The 10 strips 11 are threaded therethrough as shown in Figure 4, before being curled to the can body. These strips therefore limit the lowermost movement of the bottom in the can, and the bottom and lower cover therefore form a compartment 15 in the can for matches, if desired.

These strips are quite resilient, they may be made of very thin metal, and they have heads 13 to prevent them from pulling through slots 12. They also have shoulders 14, or in the alternative, 20 a plurality of shoulders 15, as shown in Figure 9. When the can is first packed, the strips are folded over on the bottom, as shown in Figures 4 and 8, and the packaged material 16 is then placed in the can. When the material has been used to an 25 extent where it is hard to reach or remove from the can, the bottom is pushed up. This action straightens out the strips, lengthwise, and slightly curls them, so that they assume somewhat the shape of the side of the can. This curling 30 strengthens them materially in withstanding downward pressure of the bottom when they hold it up. When the bottom is pushed up beyond shoulder 14 or any of shoulders 15, the shoulder tends to straighten out when it is released by 35 flange 10, and this straightened shoulder then bears up firmly under the flange. In the drawings the flange is shown slightly above the shoulders to illustrate their operation.

Although I have described this device in detail, 40 it will be apparent to those skilled in the art that many modifications may be made therein without departing from the inventive idea disclosed herein.

45 I claim:

1. A container having resilient strips extending into the container and attached thereto adjacent the bottom thereof, a bottom slideable in the container, means on said bottom to transversely bend said strips, shoulders on said strips to limit the 50 downward movement of said bottom after said bending means has been pushed up beyond said shoulders to release said shoulders therefrom.

2. A container having resilient strips extending into the container and attached to the bottom 55

thereof, a bottom slideable in the container having constraining means thereon including slots to receive said strips therethrough, said constraining means bending the strip transversely, said strips having shoulders thereon to limit the downward movement of said bottom after the constraining means have been pushed up beyond said shoulders to release said shoulders therefrom.

3. A container having resilient strips extending 10 into the container and attached to the bottom thereof, a bottom slideable in the container having constraining means thereon including slots to receive said strips therethrough, said constraining means bending the strip transversely, said strips 15 having shoulders thereon to limit the downward movement of said bottom after the constraining means have been pushed up beyond said shoul-

ders, to release said shoulders therefrom and means on said strips to limit the upward movement of said bottom.

4. A container having parallel sides and a slideable bottom therein having a depending flange, 5 openings in said flange, resilient strips extending upwardly in said container and through the openings in said flange, and having shoulders thereon to limit the movement of said bottom, the lower ends of said strips being rolled into an outwardly directed bead surrounding the lower end of the container, a cover having curled edges extending over said bead on the parallel sides of said container and sliding on the same, thereby forming an auxiliary compartment in said container. 15

WILLIAM FROEHLICH.
